UNITED STATES PATENT OFFICE

2,455,045

HAND SEALER FOR CONTAINERS

John Coyle, Baltimore, Md., assignor to Continental Can Company, Inc., New York, N. Y., a corporation of New York

Application July 6, 1945, Serial No. 603,549

2 Claims. (Cl. 113—24)

1

The invention relates to new and useful improvements in a hand operated sealer for attaching a closure cap to the nozzle of a container.

An object of the invention is to provide a hand sealer which can be supported on the container end in a centered position relative to the nozzle to be closed, which hand sealer is provided with manually rotatable curling rollers for attaching a closure cap to the nozzle of the container.

A further object of the invention is to provide a sealing head of the above type wherein a cam for controlling the curling rollers is manually operated.

These and other objects will in part be obvious and will in part be hereinafter more fully disclosed.

In the drawings,

Figure 1 is a side view of a hand sealer embodying the improvements, the hand sealer being shown as placed on a container for closing the same;

Figure 2 is a top plan view of the hand sealer and container;

Figure 3 is a sectional view on the line 3—3 of Figure 2 showing the curling rollers in their final position for securing the cap to the nozzle of the container;

Figure 4 is a view in part similar to Figure 3 but showing the curling rollers retracted;

Figure 5 is a sectional view on the line 5—5 of Figure 4;

Figure 6 is a sectional view through a container nozzle showing a closure cap applied thereto; and

Figure 7 is a sectional view through the closure cap and nozzle centrally through one of the tearing tabs.

The invention is directed particularly to a hand sealer for securing a closure cap to the nozzle of a relatively large container wherein the nozzle is located adjacent the periphery of the container. The container, as illustrated in the drawings, is square in cross section.

The container includes a body portion 1 to which an end 2 has been secured by a double seam 3. The container is provided with a nozzle 4 preferably located near one corner of the container. This nozzle is rolled outwardly into a hollow bead 5.

The container is sealed by a closure cap which includes a body portion having a central depression 6 surrounded by a vertical wall 7. This vertical wall 7 is dimensioned so as to fit closely within the inner surface of the nozzle. The depression is of sufficient depth so that the bottom 8 thereof is below the hollow bead on the nozzle when the cap is in place. The cap is also provided with a depending skirt 9 which is spaced from the vertical wall 7 so as to provide a channel for a sealing compound 10. The skirt initially is parallel with the vertical wall 7 and is of a length

2

so that it extends below the bead on the nozzle as indicated in broken lines in Figure 6. The closure cap is placed on the nozzle and the sealing compound brought into contact with the hollow bead, after which the skirt is curled underneath the bead by curling rollers to the position shown in Figure 6. This seals the container.

The closure cap 6 is provided with score lines 11, 11 which extend from the outer edge of the skirt into the bottom of the depression and preferably all the way across the cap. These score lines are parallel and set off therebetween a tear strip 12. The tear strip is provided with tab extensions 12a at the ends thereof.

The closure cap is disclosed and claimed in my copending application Serial No. 606,117, filed July 20, 1945, and further description thereof is not thought necessary.

The present invention has to do with a hand sealer for curling the skirt of the closure cap around the bead for the sealing of the container. The hand sealer includes a frame 13. This frame is more or less of a skeleton construction. It includes a base member 14 which is adapted to rest on the double seam of the container. At spaced intervals this base member 14 is provided with depending members 15 which center the sealing head on the container.

Mounted on the supporting frame is a sealing head which includes a chuck 16. This chuck is mounted at the lower end of a shaft 17 so that the chuck may remain stationary while the shaft is rotated. Mounted on this shaft is a head member 18 which is secured to the shaft by a pin 19. Between the head member 18 and the chuck 16 is a ball bearing 20. Also mounted on the shaft 17 is a sleeve 21. Attached to the sleeve is a handle 22. Said handle is splined to the sleeve so that the sleeve may be rotated by means of the handle. This sleeve is secured to the shaft 17 by means of a pin 23 carried by the shaft and engaging in elongated slot 24 in the sleeve.

Mounted on the head 18 are a plurality of levers 25. These levers are pivoted to the head 18 by pivot pins 26. Each lever carries a curling roller 27 provided with a curling groove 28. A spring 29 associated with each lever serves to move the curling rollers outwardly away from the chuck 16. A cam 30 carried at the lower end of the sleeve 21 is adapted to engage a cam face 31 on the levers and, when this cam 30 is lowered, the levers will be forced outwardly at their upper ends and this will cause the curling rollers to engage the skirt of the closure cap and spin the same around the bead on the nozzle.

A spring 32, housed partly in the rotatable head 18 and partly in the cam 30, serves to raise the cam and the sleeve 21 on which it is mounted. Attached to the sleeve is a collar 33. The sleeve

21 is mounted for rotation in a bushing 34 carried by the frame 13.

A hand operated lever 35 is pivoted at 36 to the frame 13 and this lever carries pins 37 which extend into an annular groove 38 in the collar 33. The lever 35 is raised by means of a spring 39.

After a cap has been placed on the nozzle, then the sealing head is placed on the can end and the members 15 on the sealing head base will center the chuck 16 relative to the nozzle so that the chuck will extend into the depression 6 in the closure cap. The operator then grasps the handle part 13a of the main frame and the lever 35 and moves the lever downwardly toward the frame. This will move the sleeve 21 downwardly through the connection of the lever to the collar 33. The downward movement of the sleeve will cause the cam 30 to engage the levers supporting the curling rollers. At the same time that this cam moves the curling rollers into engagement with the skirt of the closure cap, the sleeve 21 and the shaft 17 are rotated through the aid of the handle member 22. This does not rotate the chuck but it does rotate the sealing head 18 and parts carried thereby and also the control cam 30. As these curling rollers move around the peripheral edge of the skirt the operator continues to press the lever 35 downwardly and this will cause the curling rollers to move inwardly and complete the curling of the skirt around the bead on the nozzle.

As soon as the rollers complete their curling action, which is determined by hand pressure on the lever 35, then the lever is released and the springs will raise the lever and the cam and cause the rollers to move away from the closure cap so that the sealer can be removed from the container.

When it is desired to open a container then the tear strip is removed and this will release the remaining sections of the cap so that they may be readily moved radially to release the grip of the curled skirt on the bead. The closure cap thus can be removed without in any way disturbing the bead on the nozzle.

The provision of a hollow bead on the nozzle readily adapts this sealing means to reclosure of the container. When it is desired to reclose the container a new sealing cap is placed thereon and the sealing head applied and, inasmuch as the hollow bead has not been disturbed in any way in the removal of the cap, the skirt may be curled into tight engagement with the bead on the nozzle. During the first operation of sealing the container the bead may be contracted somewhat due to the pressure of the curling rollers and may remain in the contracted position. This does not interfere with the forming of a tight seal for the reclosure for the reason that the curling rollers are moved into engagement with the skirt of the closure cap by the hand operated lever and it can be moved downwardly until a tight seal is accomplished.

It is obvious that many changes in the details of construction may be made without departing from the spirit of the invention as set forth in the appended claims.

I claim:

1. A hand sealer for container closures comprising a supporting frame adapted to rest on the end seam of a container having a nozzle, means carried by the frame for preventing lateral movement thereof on the end seam, said frame having a bearing centered directly over the nozzle of the container, a sleeve mounted in said bearing for

rotation and for endwise movement, a crank attached to the sleeve for rotating the same, a hand operated lever pivoted to the frame and connected to the sleeve for moving said sleeve endwise, a shaft mounted in said sleeve and means for connecting the shaft to the sleeve whereby the shaft is rotated with the sleeve and the sleeve is permitted to move endwise of the shaft, a sealing head mounted on said shaft and rotatable therewith, a chuck carried by the shaft and sealing head so that the shaft and head may rotate relative to the chuck, a plurality of seaming levers carried by said head, curling rollers carried by said levers, springs associated with the levers for moving the curling rollers radially outwardly away from the chuck, and a control cam carried at the lower end of said sleeve and adapted to engage the upper ends of said levers for moving the curling rollers inwardly toward the chuck.

2. A hand sealer for container closures comprising a supporting frame adapted to rest on the end seam of a container having a nozzle, means carried by the frame for preventing lateral movement thereof on the end seam, said frame having a bearing centered directly over the nozzle of the container, a sleeve mounted in said bearing for rotation and for endwise movement, a crank attached to the sleeve for rotating the same, a hand operated lever pivoted to the frame and connected to the sleeve for moving said sleeve endwise, a shaft mounted in said sleeve and means for connecting the shaft to the sleeve whereby the shaft is rotated with the sleeve and the sleeve is permitted to move endwise of the shaft, a sealing head mounted on said shaft and rotatable therewith, a chuck carried by the shaft and sealing head so that the shaft and head may rotate relative to the chuck, a plurality of seaming levers carried by said head, curling rollers carried by said levers, springs associated with the levers for moving the curling rollers radially outwardly away from the chuck, a control cam carried at the lower end of said sleeve and adapted to engage the upper ends of said levers for moving the curling rollers inwardly toward the chuck, and yielding means adapted to move the cam away from the seaming levers when the hand operated lever is released.

JOHN COYLE.
